UNITED STATES PATENT OFFICE

DENNIS L. RYAN AND ALFRED CROSSLEY, OF WASHINGTON, DISTRICT OF COLUMBIA,
ASSIGNORS TO WIRED RADIO, INC., OF NEW YORK, N. Y., A CORPORATION OF DELA-
WARE

PIEZO ELECTRIC CRYSTAL APPARATUS

Application filed December 22, 1928. Serial No. 327,935.

Our invention relates broadly to piezo electric crystal apparatus and more particularly to a construction of holder for piezo electric crystals.

One of the objects of our invention is to provide a construction of piezo electric crystal holder which is particularly adapted for sustaining oscillations within a frequency band of 150 to 6500 kilocycles.

Another object of our invention is to provide a construction of piezo electric crystal holder having means for centering a piezo electric crystal element within a container while relieving the effect of damping upon the piezo electric crystal element.

Still another object of our invention is to provide a holder for a piezo electric crystal in which all adjustable parts are screw threaded into metallic screw threaded guides for permitting an accurate adjustment of the parts within the holder.

A further object of our invention is to provide a construction of piezo electric crystal holder adapted for mounting in a standard electron tube socket, where the holder has a rugged construction and is capable of shipment without breakage of the piezo electric crystal carried within the holder.

Other and further objects of our invention reside in the construction of piezo electric crystal holder as set forth in the specification hereinafter following by reference to the accompanying drawings in which:

Figure 1 is a plan view of the piezo electric crystal holder of our invention; Fig. 2 is a side elevation of our piezo electric crystal holder; Fig. 3 is a longitudinal cross-sectional view taken through the piezo electric crystal holder; and Fig. 4 is a lateral cross-sectional view on line 4-4 of Fig. 3.

Our invention is directed to the construction of a piezo electric crystal apparatus of the general class set forth in Letters Patent No. 1,572,773, to Alfred Crossley, dated February 10, 1926, and in Letters Patent to C. B.

Mirick and Alfred Crossley, No. 1,683,093, dated September 4, 1928. We have, however, considerably improved the structure of the piezo electric crystal holder set forth in the above patent for improving the efficiency of 50 operation of the piezo electric crystal apparatus and insuring the protection of the piezo electric crystal against damage in the course of shipment of the crystal to the place of installation.

Our present construction of piezo electric crystal holder may be mounted in an electron tube socket and has proven highly satisfactory for use with crystals which sustain oscillations within a frequency range from 150 60 to 6500 kilocycles. The crystal holder is extremely simple in its construction, has a low manufacturing cost and a high degree of ruggedness and may be readily adjusted. The adjustable parts are all accurately tapped 65 into metallic bushings avoiding the generation of minute particles which tend to be broken off during adjustment when a metallic member is threaded into an insulated body portion, as has heretofore been the practice in 70 crystal holders, which particles tend to work their way under the crystal, that is, between the surface of the crystal and the electrodes, and stop the crystal from oscillating. We provide an adjustable member which serves 75 to locate the crystal adjacent one end of the casing while eliminating any effects of damping by reason of the proximity of the adjustable guide with respect to the surface of the crystal.

Referring to the drawings in detail, reference character 1 designates an insulated body structure upon which the parts of the piezo electric crystal apparatus are mounted. A threaded ring member 2 is positioned in one 80 end of the cylindrical body 1 to receive the threaded end plate 3 substantially in the form of a plug for closing the end of the casing. The end plate 3 is removable by grasping the narrow peripheral edge 4. The in- 85

inner surface 5 of the end plate 3 provides a support for the piezo electric crystal element 6 which has its lower surface resting in contact with the upper surface of the plate 3. The piezo electric crystal 6 may be in the form of a disc or a parallelopiped. Connection is made to the upper surface of the piezo electric crystal by means of a plate member 7 which rests upon the surface of the crystal. The opposite end of the insulated casing 1 is provided with a cutaway shoulder portion 8 to receive the cylindrical portion 9 from which project pins 10 which serve as stops when the piezo electric crystal holder is inserted in the standard bayonet type vacuum tube socket. The cylindrical portion 9, which may conveniently be metallic, is substantially in the form of an end cap having a central annular shoulder portion 11 thereon which is tapped at 12 to receive the threaded stud member 14 which projects from the rotatable plate or guide 15. The plate 15 is cut away at its under surface as represented at 16 and is surrounded by an annular shoulder or flange 17 which approaches the peripheral edge of the contacting electrode 7 of the piezo electric crystal apparatus. The electrode plate 7 is provided with a plurality of apertures 18 arranged in a circle about the stud 14, which apertures permit the free passage of air between the chamber in which the piezo electric crystal element is mounted and the area at the opposite end of the chamber above the plate 15. The apertures or perforations permit the free intercommunication of vibrations between the piezo electric crystal chamber and the upper portion of the holder and eliminate reflection of sound waves from the crystal. We have found that where the reflection and damping phenomena are not eliminated the oscillation characteristics of the crystal will be impaired. A flexible connection is taken from the plate 15 to the electrode 6 as represented at 19. The end of the stud 14 is slotted as indicated at 20 to permit the accurate adjustment of the plate 15 with respect to the piezo electric crystal. After the adjustment has once been fixed the setting thus selected is made permanent by filling the well 21 around the head of the stud 14 with solder or other molten metal, as represented at 22. The top of the casing is then protected by a bakelite cover as shown at 23 which is secured to the cylinder portion 9 by means of the screw 24. Electrical connection is made with the opposite surface of the piezo electric crystal element 6 through the lower surface of the end plate 3 and through the projecting studs 10 which are at opposite potential with respect to the end plate 3. The retaining member or plate 15 is so constructed that the piezo electric crystal 6 cannot jump clear of the upper electrode 7 because by screwing down on the stud 14 a minute clearance is

obtained between the upper electrode 7 and the shoulder or flange 17. This small clearance allows free vibration of the piezo electric crystal without restriction but permits a minimum amount of play and practically 70 keeps the crystal in the same relative position and reduces the chance of breakage in transit to a minimum. The crystal may in this way be protected when the holder is shipped to the place of installation after having been 75 adjusted at the place of manufacture.

We have found the piezo electric crystal apparatus of our invention to be highly efficient in its operation and practical in construction, and while we have described a 80 specific embodiment of the invention we desire that it be understood that modifications may be made and that no limitations upon our invention are intended other than are imposed by the scope of the appended claims. 85

What we claim as new and desire to secure by Letters Patent of the United States is as follows:

1. In piezo electrical crystal apparatus, in combination, a circular metallic base plate 90 provided with circumferential threads, an annular insulating body structure, a tapped metallic ring secured to one end of said body structure and engaging said threads of said base plate, a centrally tapped metallic cap 95 secured to the opposite end of said body structure, a piezo electric crystal supported upon said base plate, an upper electrode adjacent the upper surface of said crystal, a restraining plate adjacent said upper electrode and provided with a threaded central stud engaging said tapped portion of said cap, whereby the relative positions of said base plate and said restraining plate may be controlled by screw thread adjustments involving only the bearing of metal upon metal. 100

2: In piezo electric apparatus, in combination, an annular insulating body structure of smooth bore, a circular metallic base plate provided with circumferential threads, a 110 tapped metallic ring secured to one end of said body structure and engaging said threads of said base plate, a centrally tapped cap carried by the opposite end of said body structure, a piezo electric crystal supported upon said base plate, an upper electrode adjacent the upper surface of said crystal, and a restraining plate adjacent said upper electrode and provided with a threaded central stud engaging said threaded portion of said cap. 115

3. In piezo electric crystal apparatus, in combination, a circular metallic base plate provided with circumferential threads, an annular insulating body structure, a metallic ring secured to one end of said body structure, and adapted to engage said threads of said base plate, a centrally tapped metallic cap secured to the opposite end of said body structure, a piezo electric crystal supported upon said base plate, an upper electrode ad- 125

5 jacent the upper surface of said crystal, a restraining plate adjacent said upper electrode and provided with a threaded central stud engaging said tapped portion of said cap, the head of said central stud being slotted whereby the position of said restraining plate may be adjusted from the outside of said cap.

10 In testimony whereof we affix our signatures.

DENNIS L. RYAN.
ALFRED CROSSLEY.
